United States Patent Office

Des. 196,964
Patented Nov. 26, 1963

196,964

KNOB

La Verne E. Clayton, Rockford, Ill., assignor to Amerock Corporation, Rockford, Ill., a corporation of Illinois

Filed May 16, 1963, Ser. No. 74,919

Term of patent 14 years

(Cl. D10—8)

FIGURE 1 is a front elevational view of a knob incorporating my new design.

FIG. 2 is a side view of the knob as viewed from the left in FIG. 1.

FIG. 3 is a sectional view taken along the line 3—3 in FIG. 1.

FIG. 4 is a sectional view taken along the line 4—4 in FIG. 1.

FIG. 5 is an enlarged perspective view of the knob.

I claim:

The ornamental design for a knob, substantially as shown.
